UNITED STATES PATENT OFFICE

2,645,894

WINDING MECHANISM FOR SELF-WINDING WATCHES

Marc Philibert Huguenin, Geneva, Switzerland,
assignor to Montres Rolex S. A. (Rolex Watch
Co. Ltd.), a corporation of Switzerland

Application January 26, 1949, Serial No. 72,857
In Switzerland June 10, 1948

1 Claim. (Cl. 58—82)

1

The present invention relates to a winding mechanism for self-winding watches with a movable winding weight.

It is an object of the invention to provide a novel and efficient automatic winding mechanism for self-winding watches.

A further object of the invention is to provide a winding mechanism of simple and rugged construction whereby the winding weight actuates the winder of the watch over the major part of its rotational movement.

According to the invention, the winding weight drives a cam having a periphery forming at its major part a curve of gradually increasing radius, the ends of which curve being connected by a short, steeply inclined slope, which cam cooperates with a cam follower actuating a ratchet wheel belonging to the winder of the watch.

These and other features and advantages of the novel winding mechanism according to the present invention will appear from the following description and claims in conjunction with the accompanying drawing, which illustrates by way of example an embodiment of the invention.

In the drawing:

Figure 1 shows a plan view of the winding mechanism of the watch from the side of the bridges.

Figure 2 shows a section along the lines II—II of Figure 1, portions being broken away for reasons of clearness.

The oscillating weight, designated as 1, has a half circular disc-like form and is pivotally mounted and freely rotatable on a pin 2 carried on a bridge 3 of the watch. Coaxially with the weight 1, a cam 4 is pivotally mounted on a cylindrical bush 23 at one end provided with a flange by means of which the bush is also fastened to the bridge 3. The periphery of the cam 4 presents for the greater part a curve of gradually increasing radius, the two ends of this curve designated as 5a and 5b, respectively, being connected by a short slope 5c of steep inclination (Figure 1). The profile of the periphery of the cam 4 has a triangular form as shown in Figure 2, corresponding to a groove of triangular cross-section in a roller 12 lying against the periphery of the cam. The cam 4 is coupled by means of a free wheel arrangement to the winding weight 1 in such a way that it is taken along by the weight rotating in the direction of the arrow 6, but is retained when the weight moves in the opposite direction. To this effect the cam is provided on both of its flat faces with a ring of upright ratchet teeth 7 and 8, respectively, the teeth 7

cooperating with a corresponding flat upright spring 9 mounted on the weight 1, and the teeth 8 cooperating with a corresponding flat upright spring 10 mounted on the flange of the bush 23 fastened to the bridge 3. The spring 9 engaging one of the teeth 7 drives the cam 4 on rotation of the weight 1 in the direction of the arrow 6, the spring 10 meanwhile skipping over the teeth 8; the weight 1 meanwhile turning in the reverse direction, the cam 4 is retained by the spring 10 engaging one of the teeth 8.

The roller 12 cooperating with the cam 4 is pivotally carried by an arm 11a of a pivotally mounted lever 11, which roller is held in contact with the cam by means of a spring 13 acting on a second arm 11b of the lever 11.

The lever 11 has a hole 18 of a non-circular elongated cross-section, the eccentric part of said hole lying opposite the arm 11b. Through this hole passes a hollow shaft 19 fastened to the barrel bridge 20 of the watch and serving as a pivot for the lever 11. Rotatably mounted on the same shaft 19 are a ratchet wheel 15 and a pinion 16 rigidly connected to the ratchet wheel, the ratchet wheel 15 cooperating with a pawl 22 permitting it to turn but in one direction, and the pinion 16 engaging the barrel wheel 17 of the watch. The lever 11 and the moving body 15, 16 are axially kept in place by a screw 24 passing through the hollow shaft 19 and resting with its head on the lever 11.

The arm 11b of the lever 11 has the form of a circle segment and is provided with an internal tooth 14 of inwardly pointing ratchet teeth lying in the same plane as the ratchet teeth of wheel 15 and cooperating therewith. The elongated hole 18 permits a radial displacement of the lever 11 with respect to the shaft 19 in a direction along the axis of the arm 11b in such a way that the tooth 14 may skip over the teeth of the ratchet wheel 15 when the lever is turned contrary to the direction of the arrow 21.

The winding mechanism operates as follows:

When the winding weight 1 rotates in the direction of the arrow 6, for instance as a result of a movement of the wrist the watch is worn on, the spring 9, engaging one of the teeth 7 on the cam 4, rotates the cam in the same direction. The lever arm 11b pressing with its roller 12 against the periphery of the cam 4 is consequently moved outwardly in the direction of the arrow 21 and the lever 11 is turned around its pivot 19 over a small angle, as the radius of the periphery of the cam 4 increases at the contact point of the roller 12 and the cam. The

toothing 14 of the lever arm 11b engages the teeth of the ratchet wheel 15 and takes this wheel along, so that through the pinion 16 and the barrel wheel 17, winding takes place. When the end 5b of the curve of the cam periphery reaches the roller 12 (position as shown in Figure 1), the spring 13 moves the lever in the direction opposite to the arrow 21 as the roller rolls along the short slope 5c. During this short reversal of the movement of the lever 11, the teeth 14 skip over the teeth of the ratchet wheel 15, the latter being retained by the pawl 22. As soon as the roller 12 encounters the point 5a of the cam periphery, winding of the watch is resumed.

When the weight rotates in the direction opposite to that of the arrow 6, the cam 4 is not taken along, the spring 9 skipping over the teeth 7 of the cam. During this movement of the weight, the cam is retained by the spring 10 engaging one of the teeth 8.

As will be apparent from the above description, an advantage of the winding mechanism of the present invention forms the fact that winding occurs on the major part of the periphery of the cam 4 moving along the roller 12, the lever 11 being quickly returned to its initial position when the roller leaves the short, steep slope 5c.

What I claim and desire to secure by Letters Patent is:

In a self-winding watch comprising a cam con-

trolled by a winding weight, a swinging lever the oscillations of which are produced by said cam, a ratchet wheel belonging to the winder of the watch and mounted coaxially with said swinging lever, a toothed sector on said lever, coaxial with said ratchet wheel and carrying inwardly directed ratchet teeth intended to engage with said ratchet wheel, a double acting spring cooperating with said lever for applying it against said cam and for engaging the teeth of the toothed sector with said ratchet wheel, a pivot for said lever, this latter being mounted on said pivot by means of a hole of elongated cross-section, the eccentric part of said hole lying opposite said toothed sector, whereby said lever can move radially with respect to said ratchet wheel, against the action of said spring, and thus disengage the toothed sector from said wheel.
